[57] CLAIM

The ornamental design for a sectional sofa corner piece, as shown and described.

DESCRIPTION

FIG. 1 is a perspective view of a sectional sofa corner
piece of my new design;

FIG. 2 is a front elevational view thereof;

FIG. 3 is a rear elevational view thereof;

FIG. 4 is a top plan view thereof;

FIG. 5 is a left side elevational view thereof, taken from line 5—5 of FIG. 4; and,

FIG. 6 is a right side elevational view thereof, taken from line 6—6 of FIG. 4.
